UNITED STATES PATENT OFFICE.

VAN BUREN JACKSON, OF PEDRO MIGUEL, CANAL ZONE, ASSIGNOR TO SAN DIEGO CONSOLIDATED GAS AND ELECTRIC CO., OF SAN DIEGO, CALIFORNIA, A CORPORATION OF CALIFORNIA.

LINEMAN'S DEVICE.

1,223,791.

Specification of Letters Patent. Patented Apr. 24, 1917.

Application filed April 24, 1916. Serial No. 98,101.

To all whom it may concern:

Be it known that I, VAN BUREN JACKSON, a citizen of the United States, and resident of Pedro Miguel, Canal Zone, Panama, Central America, have invented certain new and useful Improvements in Linemen's Devices, of which the following is a specification.

This invention relates to appliances such as are used by linemen for making a connection or tap from a high line wire while the current is flowing through it.

Such a connection is usually effected by twisting a tap wire about the main and soldering to form a connection to lead the current off from the line. According to my invention I provide a novel clamp, one of the novel features of which is that it is open upon its side. The operation of making the connection consists substantially in securing the tap wire in the clamp and raising the clamp to the height of the line wire, then moving the clamp laterally onto the line wire, and securing the clamp to the wire.

A principal object of this invention is to provide simple and efficient devices for effecting such a connection, and which can be readily handled and operated without danger to the lineman. My novel clamp is preferably provided with a screw for securing it to the line wire; and one of the objects of the invention is to provide simple means for operating this screw from a point well below the line wires where the linemen will be subjected to no risk of touching adjacent wires. A further object is to provide the device with simple means for holding the clamp and for protecting it from becoming dislodged but operating in such a way as to permit the device to be readily freed from the clamp after it has been attached to the line wire.

Further objects of the invention will appear hereinafter.

In the drawing, which illustrates one embodiment of my invention,

Figure 1 is a perspective indicating how the device is used in practice.

Fig. 2 is a side elevation and partial section of the upper part of the device.

Fig. 3 is a perspective showing a connection or tap such as may be effected by employing my devices.

The purposes and functions of my devices will be better appreciated if the general purposes and construction of my attaching

clamp are first described. This clamp is a double clamp of simple construction comprising clamping means for holding the drop wire, that is the tap wire, and clamping means for securing the clamp to the line wire.

My holder device affords means for holding this clamp so that the same can be raised, applied to, and secured to the line wire. To this end I give the clamp and the holder a correlated form, that is to say, the clamp and the holder are constructed to coöperate together in enabling the holder to temporarily hold the clamp.

By way of example I shall describe my device when intended to be employed for attaching a clamp of the form such as that shown in Fig. 3. This novel clamp has an elongated body with a bore or socket 2 to receive the "tap" wire 3 which may if desired be permanently held in the socket by any means desired, for example, set screws 4. This clamp is open its full length on one side so as to form a channel between two fixed jaws 7 and 7^b to enable the clamp to be applied to the line wire 5 by a lateral movement toward the wire. In order to enable the holding device to hold the clamp in applying it to the wire the outer sides of the jaws 7 and 7^b are preferably flat and substantially parallel to each other, which enables them to coöperate with a holder of simple form.

One of the fixed jaws is provided with means capable of interlocking with an actuating device on the clamp holder so that when actuated it will secure the clamp to the line wire. For this purpose I prefer to provide a movable jaw or clamping plate 7^a which extends longitudinally in the channel 9 and is pressed forward by a set screw 6 which is attached in one of the fixed jaws, and screws toward the other fixed jaw. This set screw has a head of a form that enables it to interlock with an actuating device operable from a point remote from the line wire.

My holder device preferably comprises a head 8 supported upon an insulating handle 9 preferably in the form of a bar of wood of suitable length.

The head 8 is preferably provided with means correlated to the clamp in form for yieldingly holding the clamp. This means is preferably in the form of resilient jaws 10, and 11 which may be formed of bent

spring plate. These jaws preferably project laterally from an integral connecting resilient bow 12 and they also preferably converge slightly, one of the jaws, for example, jaw 10, being provided with an inwardly convex bill 13 which approaches the opposite jaw in such a way that a throat of reduced width is formed between the jaws. Evidently, the clamp 1 may be moved laterally through the throat so as to be yieldingly held between the jaws.

In order to protect the jaws 10 and 11 from being struck or bent accidentally, I prefer to provide rigid members 14 in the form of jaws in which the yielding jaws lie. The members 14 preferably form integral forks extending up from the head. By means of the bar 9 and the head 8 the clamp may be supported and applied to the line wire.

The handle or bar 9 is preferably provided with means for operating a movable part of the clamp (such as screw 6) from a safe point remote from the line wire in order to secure the clamp to the line wire. For this purpose I prefer to provide a movable part carried by the bar 9 and operable from the lower end of the bar. To do this the bar 9 is preferably tubular and carries in its interior a shaft 15 which is also preferably of insulating material such as wood. This shaft is constructed to shift longitudinally in and also rotate in the bar 9. The upper end of the shaft has a cap 16 for interlocking with and actuating the screw 6. This cap may be of metal formed with a cross slot 17 for engaging the set screw, 6, which by the way, is located on the under side of the clamp and has a wing-head to engage the slot. The lower end of the shaft 15 preferably carries a small hand wheel 17 which enables the cap 16 to be raised to engage the screw and then rotated to secure the clamp to the wire. After the clamp is secured the shaft 15 may be pulled down to disengage its cap from the screw, and the head can then be moved laterally to disengage it from the jaws 10 and 11. For convenience the spring jaws 11 may be attached to the rigid jaws 14.

In order to facilitate the attaching of the clamp 1 to the wire 5, it is desirable to provide a single clamping screw 6, but on this account it is desirable to provide the movable jaw 7^a with means for guiding it on its corresponding fixed jaw 7. For this purpose the ends of the jaw 7 are preferably provided with notches 19, and the ends of the clamping plate 7^a are preferably provided with downwardly bent extensions 20 which lie in these notches. And in order to prevent the clamping plate 7^a from becoming dislodged from the notches, I prefer to provide the lower ends of the extensions 20 with laterally projecting fingers 21, which will engage the under sides of the jaw 7 at its

ends and retain the plate in the clamp. The plate 7^a is preferably of resilient material so that the extensions 20 can be sprung outwardly to enable the plate to be passed laterally into position between the jaws 7 and 7^b; when the extensions 20 are released they will then spring into the notches 19. By employing this clamping jaw, I am enabled to secure a relatively large area of contact between the line conductor 5 and the clamp 1, although I employ a single fastening device or screw 6.

It is understood that the embodiment of the invention set forth herein is only one of the many embodiments the invention may take, and I do not wish to be limited in the practice of my invention to the particular embodiment set forth.

What I claim is:—

1. A lineman's device for making a connection to a high potential live line wire consisting of a clamp having means for securing a tap wire thereto, said clamp further having a pair of elongated oppositely disposed jaws disposed one above the other with a channel extending longitudinally between said jaws constructed to receive the line wire in a position extending longitudinally in said channel between said jaws when the clamp is moved laterally onto the wire, the outer sides of said jaws being substantially flat and parallel with each other to enable the clamp to be held yieldingly in a holding device engaging the said outer sides of said jaws, the lower one of the said jaws having screw means attached thereto for securing the line wire in said channel, said screw means having a form to detachably interlock a screw-rotating device.

2. In a lineman's device, the combination of a clamp having means for securing a tap wire thereto, and having a pair of oppositely disposed jaws to receive the line wire therebetween, a holder for the clamp having a head, said head and said clamp being of correlated form to coöperate in enabling said head to temporarily hold said clamp in applying the same to the line wire, said clamp having securing means, and said holder having insulated actuating means for interlocking said securing means to actuate the same from a point remote from said head to secure the clamp to the line wire.

3. A lineman's device for making connection to a high potential live line wire, consisting of a clamp having a bore to receive a tap wire, and having means for securing the tap wire in said bore, said clamp being open on its side to enable it to be applied by a lateral movement to the line wire, and having a fixed jaw to engage the line wire on one side, said clamp further having a clamping jaw guided on said clamp, and a clamping screw mounted in the under side of said clamp having a wing-head below to inter-

lock with a slot in an actuating part and engaging at its upper end with said movable jaw to clamp the same against the line wire.

5 4. A holding device for permanently connecting a tap wire to a high potential live line wire, consisting of an insulating handle, a head carried thereby having means for detachably holding a clamp which is to be attached to the wire, and means mounted on said handle for securing the clamp to the live wire before disengaging the holding device from said clamp.

10 5. A holding device for permanently connecting a tap-wire to a high potential live line wire, consisting of an insulating bar, a head carried thereby having means for yieldingly and detachably holding a clamp which is to be attached to the line wire, and means movably carried by said bar for securing the clamp to the live wire, said holding device being disengageable from said clamp so as to leave the clamp on the line wire.

20 25 6. A device for attaching a clamp to a high potential live line wire, consisting of a head having jaws for yieldingly engaging the clamp, a bar for supporting and raising

the head to apply the clamp to the line wire, and means movably carried by said bar for engaging a clamping screw on the under side of the clamp to attach the clamp to the wire.

7. A device for attaching a clamp to a high potential live line wire consisting of a head having jaws for yieldingly holding the clamp, rigid means for protecting said jaws, a tubular bar for supporting and raising the clamp, and a shaft rotatably mounted in said bar for engaging and operating a movable part of the clamp to attach the same to the line wire.

8. A device for attaching a clamp to a high potential live line wire consisting of a head having laterally projecting jaws for yieldingly holding the clamp, a tubular bar for insulatingly supporting and raising the head, and a shaft longitudinally shiftable and rotatable in said bar for engaging the clamping screw of the clamp to secure the same to the line wire.

Signed at San Diego in the county of San Diego and State of California this 5th day of April, 1916.

VAN B. JACKSON.
